UNITED STATES PATENT OFFICE.

EDGAR COCKS, OF LOS ANGELES, CALIFORNIA, ASSIGNOR TO LOS ANGELES WALL BED COMPANY, OF LOS ANGELES, CALIFORNIA, A CORPORATION OF CALIFORNIA.

FOLDING BED.

Application filed December 3, 1925. Serial No. 72,869.

This invention relates generally to bed structures, and particularly to folding beds, of the portable type, adapted to be concealed, when not in use, within a closet or recess and moved therefrom into a room for use. These are ordinarily termed "recess beds" and the desiderata is compactness and mobility.

The dominant features of beds of this type comprise a base, portably supported upon rollers, and a bed frame pivotally mounted thereon to swing in a vertical plane, being disposed vertically for storage or horizontally for use. When disposed horizontally the frame overhangs the base.

In order to occupy a minimum of storage space and be movable through standard width doors, the base is made as small and compact as possible, consistent with its functional requirements; and to facilitate in lowering and raising the bed frame, balance springs are provided between the frame and base. These are of sufficient strength to normally hold the frame in its vertically disposed position, but weak enough to be overcome by its unbalanced weight when disposed horizontally for use. The frame is pivotally supported adjacent one end and when a mattress and bedding are placed thereon its unbalanced weight is considerable, therefore, the balance springs must possess considerable tensile strength to minimize the physical effort required to raise or lower the frame and bedding between the horizontal and vertical positions. As the tensile strength of the balance springs is greatest when the bed frame is in its horizontal position, and as this tension is increasing as it is moved to this position from the vertical, their tendency is to tip the base in the same direction the frame is being moved and this is augmented by the shifting of the center of gravity of the entire structure relative to the base. To overcome this tendency either a great deal of undesirable weight must be added to the base or it must be made of a plan area so large that it cannot be conveniently stored in comparatively small recesses or easily passed through standard width doors.

With these problems in mind, my improvement is directed to certain features of the base, my object being to provide a simple and compact structure, including one or more flexible, auxiliary supporting legs,

which may be moved to folded position, 55 when the frame is vertically disposed for storage, or moved to extended position when the frame is lowered to the horizontal for use.

By this means I am enabled to utilize a 60 base of minimum plan area, and to effectively increase this area when necessary to counteract tension of the balance springs, obviating possibility of the base collapsing on the frame when it is moved for use, but 65 without sacrificing any of the desired compactness for storage or weakening the tensile strength of the balance springs to the point of requiring excessive physical effort in raising or lowering the bed frame. 70

A particular feature of the present invention is the automatic swinging action of the auxiliary leg, upon movement of the bed frame; the leg being moved from folded to extended position on downward movement 75 of the frame and vice versa upon its upward movement. Another feature is the arrangement of the leg operating mechanism whereby the leg is moved to its fully extended position and latched against accidental movement, upon slight downward movement of the bed frame, and retained in that position until the frame is again raised to nearly its full vertical position. This insures full extension of the auxiliary leg before the unbalanced weight of the frame has resulted 80 in shifting the center of gravity of the structure sufficient to tip the base, and before the greatest tension is exerted on the balance springs. 85

I show and describe a similar structure, 90 but different as to details, in a copending application filed Dec. 3, 1925, Serial No. 72,870.

In the following specification I describe 95 the details of construction, arrangement and operation of my improvement, reference being made therein to the accompanying drawings wherein I have illustrated its preferred specific embodiment. I wish it to be understood, however, that this particular embodiment is shown and described merely for the purpose of fully disclosing the general principles of my invention and that I reserve the right to make such changes and modifications 100 in structure as will properly come within the scope of the invention as defined by the claims appended hereto. 105

In the drawings:

Fig. 1 is a side elevation of my improved bed structure;

Fig. 2 is a fragmentary front elevation of the lower frame portion;

Fig. 3 is an enlarged fragmentary sectional view, taken as indicated by the line 3-3 of Fig. 2;

Fig. 4 is an enlarged sectional plan view, taken as indicated by the line 4-4 of Fig. 2;

Fig. 5 is a sectional detail, taken as indicated by the line 5-5 of Fig. 4; and

Fig. 6 is a sectional detail, taken as indicated by the line 6-6 of Fig. 4.

15 Referring now to the drawings the numeral 10 designates generally a base portably mounted upon a plurality of rollers 11. Rollers 11 may be either rigid or of the caster type. The base consists of a pair of 20 arcuate end members 12 joined by a rear transverse brace member 13 and a front transverse brace member 14. The end members 12 are made arcuate to facilitate in 25 movement of the base into and out of small recesses, such as closets and through doors of substantially standard width.

Standards 15 are rigidly supported upon the base 10, adjacent the forward ends of the 30 end members 12, and uprights 16 are mounted upon the rear ends of these members, the latter being suitably joined to form the head of the bed.

A bed frame generally designated by the 35 numeral 17, carrying suitable springs 18, is pivotally mounted upon the standards 15 through the medium of brackets 19—secured to the side frame members 17^a—engaging pivot pins 19^a carried by the standards 15. As illustrated in Figs. 1, 2 and 3 the pivotal 40 connections between the standards 15 and frame 17 are adjacent the head end of the frame, so the head end overhang is substantially equal to the height of the standards 15 above the base 10. Braces 20 may be 45 provided between the standards 15 and uprights 16 to lend rigidity to the structure.

A plurality of contractile helical springs 21 are each connected at one end to a transversely disposed member 22, carried by the 50 side frame members 17^a, and at their opposite ends to the transverse brace member 14, of the base 10, by means of a bracket 14^a. These springs I have termed "balance 55 springs" for the reason that they are provided to normally hold the bed frame 17 in its vertically disposed position, as illustrated in Figs. 1, 2 and 3, and to minimize the physical effort required to raise and lower this frame between its vertical and 60 horizontal positions, as illustrated in Fig. 1 (the horizontal position being shown in dotted lines). Any number of springs 21 may be provided to give the desired cushioning effect and the tensile strength is arranged in 65 accordance with the size of the bed, the

weight of the frame 17 with its springs 18, and the usual amount of bedding.

An auxiliary leg, generally designated by the numeral 23, preferably consisting of an arm 24 and a brace member 25, is pivotally 70 mounted upon the base 10; the arm 24 being joined to a lug 26 on the lower end of an elongated bearing member 27, by means of a pivotal pin 28, and brace member 25 being similarly joined to a lug 26^a, on the upper 75 end of member 27, by means of a pivot pin 29. The member 27 is rigidly supported upon the transverse brace member 14 and brace rods 30 may be provided between the member 14 and the upper end of member 27 80 to rigidly support it as shown. The pins 28 and 29 are necessarily coaxial and their common axis is preferably tilted slightly from the vertical, as illustrated in Fig. 2, to raise the swinging end of the auxiliary leg 85 free of the floor when in folded position, as shown in Fig. 2, and to bring it into engagement with the floor when in its fully extended position, as shown in dotted lines in Figs. 1, 3 and 4. If desired, a suitable 90 roller or caster wheel 31 may be provided on the outer end of the leg 23. Suitable bracing 32 may be provided between the arm 24 and brace 25.

A bent lever 33 is pivotally mounted at 34 95 upon a support 35, the latter carried between the transverse brace members 13 and 14 (see Fig. 4). A link 36 connects the adjacent 100 end of lever 33 with arm 24 of the auxiliary leg 23; the connection with the latter being adjacent to and slightly forward of its pivot 28. As shown in Fig. 4, movement of the lever 33 from the position shown in solid lines to that shown in dotted lines, will, through the medium of link 36, move the leg 105 23 from its folded position, shown in solid lines, to its extended position as shown in dotted lines. The fulcrum 34, of the lever 33, as well as the pivotal connections at 110 opposite ends of the link 36 with the adjacent end of lever 33 and arm 24 are so positioned that when the leg 23 is in its extended position the pivotal connection of the link 36 with the lever 33 will be slightly past a line drawn through the pivot 34 and the pivotal connection of the opposite end of the link 36 with the arm 24. By thus throwing past center the leg 23 is latched in its extended position, so that it cannot be accidentally moved towards its folded position by 115 striking an obstruction, such as the edge of a rug. A stop pin 37 may be provided to limit the forward swinging movement of the lever 33.

A contractile helical spring 38 is secured 120 at one end to an upwardly extending pin 39, carried by an extended end 40 of lever 33, and at its opposite end to a plate 41, carried 125 between the transverse brace members 13 and 14 of the base 10. This spring is disposed 130

to normally tend to swing the lever arm 33 forward, from the position shown in solid lines to that shown in dotted lines in Fig. 4; but its connection with the plate 41 is such that when the lever 33 is in its retracted position, as shown in solid lines, its longitudinal axis will lie very slightly to the rear of a line passing through pin 39 and pivot 34. Thus it will always exert a force tending to throw the lever 33 forward, but the first forward movement of the lever 33 will not require a great deal of force and, conversely, its return from the position shown in dotted lines to that shown in solid lines will require a minimum of force when nearing the position shown in solid lines.

The retractile movement of the lever 33, against the action of spring 38; from the position shown in dotted lines to that shown in solid lines (Fig. 4), is effected by means of a contact bar 43, carried by the head end bed frame member 17, engaging the pin 39; and when the lever 33 is moved to nearly the position shown in solid lines the bed frame 17 is nearing its vertical position and the tensile exertion of springs 21 is being constantly lessened. Therefore, while the spring 38 is arranged to exert considerable force in the outward movement of the lever 33 it is preferred that, on its inward movement, its primary tensioning be accomplished before the tension of springs 21 greatly diminishes.

In order to insure a full extended movement of the leg 23, as shown in dotted lines in Fig. 4, without depending entirely upon the action of spring 38 to move it over obstructions, such as the edges of rugs or wrinkles therein, I provide a toggle mechanism consisting of links 44 and 45, pivotally connected together by means of a pin 46 and pivotally secured at their opposite ends to the rear transverse brace member 13 and lever 33 by pins 47 and 48, respectively. The pin 46 extends through slots 49 in the adjacent ends of links 44 and 45 and also through a U-shaped yoke 50, through which the links extend. Links 44 and 45 are normally held in the position illustrated in solid lines in Fig. 4 by the action of a contractile helical spring 51, secured at one end to the transverse member 13, of base 10, and at its opposite end to the link 44, as shown. The force exerted by this spring is very slight, being just sufficient to hold the links in the position shown and exert a sufficient tension upon a chain or cable 52 to hold it taut.

The chain 52, or cable if such is used, is connected at one end to the yoke 50 and thence passed over a pulley 53, carried upon one of the base end members 12, up to and connected with one of the side frame members 17^a, as shown in Fig. 1.

When the frame 17 is in its vertically dis-

posed position (as shown in Fig. 1), the lever 33, link 36 and links 44 and 45 are in the positions illustrated in solid lines in Fig. 4, due to the bar 43, carried by the frame member 17, being in engagement with the pin 39 carried by the end 40 of lever 33, thereby placing the spring 38 in tension. Spring 51 is similarly in tension, holding links 44 and 45 in the position shown, exerting sufficient tension upon the chain 52 to hold it taut. Upon movement of the bed frame 17 downwardly, towards the position shown in dotted lines in Fig. 1, the bar 43 will be swung rearwardly in Fig. 4 and, due to the contractile action of spring 38, lever 33 will be swung forwardly, from the position shown in solid lines to that shown in dotted lines, which, through the medium of link 36, moves the auxiliary leg 23 from the position shown in solid lines to that shown in dotted lines. Upon this movement the head end of the frame 17 is raised and, through the medium of chain 52, will draw the links 44 and 45 from the position shown in solid lines in Fig. 4 to that shown in dotted lines. The lengths of the links 44 and 45, intermediate their pivots 47 and 48, respectively, and the inner ends of their slots 49, are each exactly one half the distance between the pivots 47 and 48 when the lever 33 is in its extreme forward position and leg 23 in its fully extended position, so that their movement from the position shown in solid lines to that shown in dotted lines, effects a full movement of the leg to its extended position; thereby insuring its full movement over any obstructions the roller 31 may meet and which may prevent spring 38 from completing this outward movement. By providing the slots 49 a certain amount of play is allowed in the links 44 and 45 so that they may pass beyond this center without exerting any backward pull upon the lever 33. While the length of chain 52 and its connections with the yoke 50 and bed frame are arranged to effect this full movement, the major portion of the movement is effected by spring 38, and only completed, when necessary, by the links 44 and 45.

To obviate possibility of any binding action of the spring 38 when the lever 33 is in the position shown in solid lines (Fig. 4) a small contractile helical spring 54 may be provided. This is connected at one end to the lever 33 on the opposite side of its fulcrum 34 from the spring 38 and at its opposite end to the front transverse brace member 14.

Having described a preferred form of my invention, I claim:

1. A folding bed, comprising a base, a bed frame pivotally mounted on the base to swing vertically thereon and overhang the base when in horizontal position, an auxiliary leg pivotally mounted on the base to

- swing from folded position, transversely of the bed, to extended position, longitudinally of the bed and beneath the overhanging portion of the bed frame, yielding means to normally hold said leg in extended position, means in connection with the bed frame to effect movement of said leg from extended to folded position, against the action of said yielding means, upon upward movement of the bed frame, and toggle means in connection with said moving means and bed frame to insure full extended movement of the leg.
2. A folding bed, comprising a base, a bed frame pivotally mounted on the base to swing vertically thereon and overhang the base when in horizontal position, an auxiliary leg pivotally mounted on the base to swing from folded position, transversely of the bed, to extended position longitudinally of the bed and beneath the overhanging portion of the bed frame, a lever fulcrumed on the base and having one arm connected to the auxiliary leg, a spring connecting the other arm of said lever with the base and acting to rock the lever to project the auxiliary leg to operative position, means on the bed frame adapted to cooperate with the lever to place said spring under tension when the frame is in folded relation to the base, a toggle connection between the base and the arm of said lever connected to the auxiliary leg, and connections between said toggle and the swinging bed frame for actuating the toggle as the frame is lowered from vertical to horizontal position to fully extend the auxiliary leg.
3. A folding bed, comprising a base, a bed frame pivotally mounted on the base to swing vertically thereon and overhang the base when in horizontal position, an auxiliary leg pivotally mounted on the base to swing from folded position, transversely of the bed, to extended position, longitudinally of the bed and beneath the overhanging portion of the bed frame, a lever fulcrumed on the base and having one arm connected to the auxiliary leg, a spring connecting the other arm of said lever with the base and acting to rock the lever to project the auxiliary leg to operative position, means on the bed frame adapted to cooperate with the lever to place said spring under tension when the frame is in folded relation to the base, and a toggle connection between the arm of said lever connected with the auxiliary leg and the base to insure full extended movement of the leg.
4. A folding bed, comprising a base, a bed frame pivotally mounted on the base to swing vertically thereon and overhang the base when in horizontal position, an auxiliary leg pivotally mounted on the base to swing from folded position, transversely of the bed, to extended position, longitudinally of the bed and beneath the overhanging portion of the bed frame, a lever fulcrumed on the base and having one arm connected to the auxiliary leg, a spring connecting the other arm of said lever with the base and acting to rock the lever to project the auxiliary leg to operative position, means on the bed frame adapted to cooperate with the lever to place said spring under tension when the frame is in folded relation to the base, a toggle connection between the base and the arm of said lever connected to the auxiliary leg, and connections between said toggle and the swinging bed frame for actuating the toggle as the frame is lowered from vertical to horizontal position to fully extend the auxiliary leg.
5. A folding bed, comprising a base, a bed frame pivotally mounted on the base to swing vertically thereon and overhang the base when in horizontal position, an auxiliary leg pivotally mounted on the base to swing from folded position, transversely of the bed, to extended position longitudinally of the bed and beneath the overhanging portion of the bed frame, spring actuated means mounted on the base and connected with the auxiliary leg for automatically moving the leg from folded position as the bed frame moves from vertical position, and means positively actuated by the bed frame for subsequently insuring full extended movement of said leg.

In witness that I claim the foregoing I have hereunto subscribed my name this 30 day of Oct. 1925.

EDGAR COCKS.
